DANIEL W. B. KURTZ, JR., OF COLUMBIA, MISSOURI

CIGARETTE WRAPPER AND A CIGARETTE MADE WITH SAID WRAPPER

Application filed May 7, 1928. Serial No. 275,767.

The present invention is in the nature of an improved and novel cigarette wrapper and of an improved and novel cigarette, a part of which cigarette construction consists

5 of the said wrapper.

The purpose of the said novel wrapper and said cigarette, resulting from the use of said wrapper, is to satisfy two already large and yet steadily growing demands of cigarette smokers for a longer cigarette than those now on the market, and for a shorter cigarette than the same. A cigarette constructed with the within embodied novel wrapper satisfies quite admirably both of these demands in the form of a single cigarette which is of a greater length than the ordinary cigarette now available to the cigarette smoking public, but which cigarette is, at the same time, capable of being easily divided by the

10 smoker into two equal pieces, each of which is, in itself, a short cigarette which yet is long enough for a comforting "short" smoke.

There is already a vast "army" of cigarette smokers which is universal in its extent consisting of office men and women, soldiers on duty and sailors, clerks of all descriptions and others engaged in every walk of life who are not permitted to smoke while on duty but who, from time to time, during the

20 day's work have a few moments of short intervals when they can lay aside their work momentarily and step into a hallway, a lavatory or upon the street nearby and take a "short" smoke. But these short intervals are not of sufficient time for a smoker to consume the ordinary cigarette, in its entirety, before he must return to his work. This results in his lighting up a cigarette, smoking as much of it as he has time for and then

30 throwing the remainder of it away, which remainder is, of course, a waste and a loss to him; and generally this wasted portion of his cigarette exceeds the portion which he has consumed and derived a pleasure from. It

40 is because of this practically universal condition existing that there exists this enormous and universal demand for a shorter cigarette than those ordinarily now found on the market. Among this class of smokers who feel the need of a shorter cigarette are also found

a host of office men and women who may, and do, smoke while on duty. This class of smokers will, almost invariably, and at frequent intervals during the day's work, light a cigarette, take a few "puffs" from it and then lay it aside while they resume the work at which they are engaged and upon which subject matter their minds are concentrating. The result of this is that the cigarette from which this sort of smoker has yet had but brief enjoyment, lies upon the ash tray until it has smoldered away and consumed itself, and the smoker has thereby lost the greater portion of the cigarette. This sort of smoker realizes this loss and because of it he has need for a short cigarette from which he can enjoy his "short" smoke without it resulting in the loss of so great a portion of his cigarette each time he must take a smoke. This improved and novel cigarette satisfies this universal demand for a shorter cigarette by having embodied in its construction two new and novel features, a greater length and a means by which it can be easily divided into two equal pieces, either of which is of sufficient length for the "short" smoke which these classes of smokers have only the time for. The length of this cigarette is approximately one-third greater than the length of the ordinary cigarette, and hence when this cigarette is divided into two shorter ones, so to speak, the smoker has two cigarettes, either of which is approximately one-half the length of the ordinary cigarette, and which is sufficiently long for him to enjoy his "short" smoke, but not of such a length that any considerable portion of it will be thrown away and wasted when he is through smoking. The said means, embodied within the cigarette's construction is in the nature of a weakened area in the wrapper fabric, located at the "midway point" between the ends of the cigarette, appearing somewhat as a "band" around the cigarette of a different shade of color from that of the remainder of the wrapper. It is along this "band" of the weakened area in the wrapper that the cigarette can be easily severed in twain. To manufacture a cigarette of such a length as would satisfy this demand for a shorter cigarette only would not

be so profitable as to manufacture one which embodies also features satisfying other demands, in a cigarette, of a different nature. For instance, there is also an enormous demand, by a different class of smokers whom we may designate as the "society and leisure" class, which is for a cigarette even longer still than the ordinary cigarette; and this improved cigarette is designed to satisfy also that demand of this class of smokers. The said band of a weaker area is, of course, constructed strong enough that it yet remains impervious to air so that the cigarette can be entirely smoked up if so desired. Just the ordinary, moderate smoker, universally found everywhere often feels the need of a cigarette even longer than those he buys on the today's market and this third class of smokers therefore will be interested in this improved cigarette, it being slightly longer than those he buys for his present use. In fact, I think this improved cigarette will be found to meet with almost and practically a universal favor from cigarette smokers in general, for the reason that every cigarette smoker needs at times a short cigarette and then, frequently at other times, he needs a long cigarette, and if he has provided himself with a pack of these improved cigarettes he finds himself at all times provided with exactly the kind of cigarette, a short one for only a "short" smoke or a long one as the occasion demands, as he needs.

This improved wrapper can be made of any desirable material of which cigarette wrappers are made; and the "filler" of this improved cigarette may be the same as that of any other kind of cigarette, or different, according to the desire of the manufacturer. The size of this cigarette also may vary according to preference and, using this improved wrapper, the cross-sectional area may be as preferred by the manufacturer. It is only in the two features, a greater length than the ordinary cigarette and the embodiment of this improved wrapper in its construction, that this improved cigarette is intended to differ from other cigarettes. And, however, I do not wish to be understood to confine myself to the particular length herein mentioned, $3\frac{2}{3}$ ", but I adopt that length for the present day needs of smokers, holding the matter of length as one subject to change when future demands of cigarette smokers should require such a change. The length of $3\frac{2}{3}$ " of a cigarette quite satisfies, at the present time, the demand for a longer cigarette; and, the cigarette being capable of an easy and smooth separation into two equal smaller cigarettes, this length also is quite satisfactory for that purpose at this time. The improved wrapper differs from the wrapper of the ordinary cigarette in two ways. It is longer. This has already been explained.

And it has embodied within its construction the said weaker area which also has been referred to and explained. In all other features it is intended to be similar to the other wrappers, as used on ordinary cigarettes. The weaker area is approximately $1/48"$ to $1/64"$ wide. This width of the area is quite sufficient for adaptation to wrappers made of the material of which such wrappers are now made. However, this width is, of course, subject to change to suit the nature and thickness of the fabric from which wrappers are made wherein the weakened area is to be embodied. With this weakened area embodied in the wrapper of the cigarette the smoker can, with his fingers, easily snap the cigarette into two equal portions which have smooth ends, look and serve as well as two short cigarettes, and thus afford him two "short" smokes without having to throw away and waste a considerable portion of his cigarette each time he desires a short smoke only. He derives a satisfying "short" smoke from one of the short cigarettes thus produced and reserves the other one for another short smoke later on.

With these and other objects in view, the invention, its construction and purposes can be more easily understood by having reference to the accompanying drawing hereto attached and made a part of this specification.

Fig. 1 is a plan view of the improved and novel cigarette wrapper involved in the invention; and Figure 2 is a perspective view, from side and end, of one of the improved cigarettes involved in the invention. The figures are approximately of the exact sizes of the objects they represent. As seen from Fig. 1, the improved wrapper is intended to be $3\frac{2}{3}$ " by $1\frac{3}{16}$ " in dimensions, rectangular in shape, and the fabric of which it is made is of course of the usual thickness of cigarette wrappers. In the figure *a*, *b*, *c* and *d* outline the wrapper in its dimensions; and *w*, *x*, *y* and *z* outline the weakened area embodied within the fabric of which the wrapper is made, and, as indicated, the width of this area is from $1/48"$ to $1/64"$, which will depend upon the manufacturer's preference, and which preference, generally, will be governed by the nature and thickness of the wrapper he is making at the particular time and upon his facilities for producing the said area in the fabric being then used by him. However, the production of the said weakened area into the fabric will not occasion any great difficulty as such areas in fabrics are being frequently produced in fabrics for other purposes.

Fig. 2 is a perspective view, from side and end, of a cigarette with one of the improved wrappers embodied in its construction. In the figure is seen the location of the novel feature therein of the said weakened area,

which appears very much as a "band" around the cigarette at the "midway point" between its ends and of a slightly different shade in color from the rest of the wrapper of
5 which it is an integral part.

I claim:

1. A cigarette wrapper having a narrow weakened smoke and air impervious area extending transversely and the entire width thereof intermediate its ends.
- 10 2. A cigarette wrapper longer than the ordinary cigarette but less than twice the length of the ordinary cigarette having a weakened smoke and air impervious area in the form of a narrow strip extending transversely and the entire width thereof intermediate its ends.
- 15 3. A cigarette longer than the ordinary cigarette but less than twice the length thereof with a wrapper having a narrow weakened smoke and air impervious area extending completely around the cigarette intermediate its ends.

In testimony hereof that I claim the invention above set forth I hereto affix my signature.
